UNITED STATES PATENT OFFICE.

HENRY N. NORTHOFF, OF COLUMBUS, OHIO.

COMBINED ANGLE-BAR NUT-LOCK AND BASE-PLATE FOR RAIL-JOINTS.

No. 889,856.

Specification of Letters Patent.

Patented June 2, 1908.

Application filed September 12, 1907. Serial No. 392,486.

To all whom it may concern:

Be it known that I, HENRY N. NORTHOFF, a citizen of the United States, residing at the city of Columbus, county of Franklin, State of Ohio, have invented an Improvement in a Combined Angle-Bar Nut-Lock and Base-Plate for Rail-Joints, and do hereby declare the following to be a full, clear, and exact description of the invention.

10 My invention relates to all and any kind or shape of rail-joint-bolt-nuts.

My object is to provide a useful safety device, simple and convenient as well as durable.

15 To these ends the novelty consists in the construction, combination, arrangement and application of same, as will be hereinafter, more fully described and particularly pointed out in the claims and the accompanying drawing.

20 In the accompanying drawing the reference characters indicate same parts of the invention in the several views.

Figure 1 represents a rail-joint with the usual splice-bars, bolts, nuts, and cross-ties, showing a front elevation of the angle-bar-nut-lock and base-plate in position and the manner of fastening the same. Fig. 2 represents a detail side elevation of a rail-joint 25 with the angle-bar-nut-lock in position. Fig. 3 is a sectional view taken on a plane indicated by the line *a—a*. Fig. 4 represents a detail elevation of the base-plate, showing the location of the holes for the admission of 30 the fastening spikes to the cross-ties. Fig. 5 is a sectional view of the base-plate, taken on a plane indicated by the line *b—b*.

35 In the embodiment of my invention, I employ in combination with any kind and shape 40 of rail-joint-bolt-nuts, a single continuous angle-bar A, made of metal, cast, rolled, forged or stamped and consisting of the vertical leg *a*, and the angle-piece *b*. This angle-bar A, when placed in right position is 45 located on the rail-joint (as shown in Figs. 2 & 3) on the same side with the bolt-nuts, running through the entire length of the rail-joint in one continuous piece and is shaped in such a way, that the vertical leg *a* of the 50 angle-bar A, lies close to the face of the splice-bar and the angle-piece *b* lies upon the foot of the rail, forming a good fitting connection between the splice-bar, rail and the angle-bar A.

55 The vertical leg *a* of the angle-bar A is provided on the upper edge with angular slots *c*

for the purpose of forming a receptacle for the bolt-nuts; the intermediate parts of the vertical leg *a*, situated between said angular slots *c* constituting locks *c¹*, these locks *c¹* standing with their vertical sides parallel to the vertical sides of the bolt-nuts are bound to hold and keep the bolt-nuts secure in position, therefore preventing the said bolt-nuts from turning or moving absolutely.

60 The angle-bar A is not limited in length to the length of the rail-joint; it may run over the rail-joint in any convenient length; in height the angle-bar A is limited to the section of the rail or rail-joint being used.

65 The vertical leg *a* of the angle-bar A does not reach through the entire length up to the head of the rail, only the center part of said vertical leg *a* situated between the two center slots *c* forming the center lock *c¹* is provided with an upward extension *d* nearly 70 abutting with the projection *e* under the head of the rail; the parts of the vertical leg *a* located to the right and left of said upward extension *d* reaching high enough to cover the 75 part of the bolt-nuts necessary to keep them secure in position. The vertical leg *a* is further provided on the outer side with a stiffening rib *f*, this stiffening rib *f* starts on the upper end of said vertical leg *a* terminating just 80 above the lower end of the slots *c* reinforcing the intermediate locks *c¹* through the entire 85 length of said vertical leg *a*; on the angle-point the angle-bar A is provided with a horizontal lip *g* acting as a filler in the space 90 at the termination of the splice-bar and the foot of the rail.

95 Both ends of angle-piece *b* of the angle-bar A are further provided with projections *h*, the center part of said angle-piece *b* has a 100 similar projection *i* with slots *j* cut in, which slots *j* serve the purpose of receiving the spikes of the rails; these slots *j* are only large enough to allow the spikes to rest in.

The end projections *h* and the center projections *i* are flattened on their tops so as to 105 form a solid base for the head of the fastening spikes.

The plate B Fig. 4, being an integral part of the device consists of a plate of uniform 110 thickness, made of metal, cast, rolled or stamped, shaped rectangularly and is provided near the ends with holes *k* and *l*, these holes *k* and *l* are square and serve the purpose of allowing to pass the fastening spikes 115 through, to be embedded in the cross-ties. The holes *k* placed on the front of the plate

B, have to correspond with the slots *j* in the center projection *i* of the angle-piece *b*, the holes *l* on the back end of the plate may be placed in any suitable space; the parallel distance between the holes *k* and *l* to be governed by the section of the base of the rail, the plate B is to be applied to.

The plate B is provided on one of its sides with a rib *m*, this rib *m*, when the plate B is placed in right position stands parallel to the angle-bar A and with its inner side fitting snugly to the lower part of the central projection *i* of said angle-bar A acts as a stop against any forward sliding motion of the angle-bar A; it can be clearly seen from the foregoing described arrangement, that once the bolt-nuts, the angle-bar and plate are fastened in place, any moving or displacing of the angle-bar is practically prevented; in upward direction, through the lower end of the slots *c* and by upward extension *d* of the angle-bar A against the rail-head; laterally both ways, through the slots *c* or locks *c* and the bolt-nuts therein and through the horizontal projections *h* on both ends and the center projection *i* on the foot of the angle-bar and the corresponding spikes driven through the baseplate B in the underlying cross-ties; and in a downward direction, through the horizontal rib *m* on the front end of the plate B and the fastening spikes driven through the plate B in the underlying cross-ties; therefore the angle-bar A safely secured from moving in whatever direction, is bound to prevent the bolt-nuts from turning or moving; consequently the purpose of the device for a safe, simple and absolute lock for rail-joint-bolt-nuts is accomplished.

Although I have specially described my invention with regards to the construction and relative arrangement of the several ele-

ments I do not desire to be confined to the same, as such changes or modifications may be made as clearly fall within the scope of my invention, without departing from the spirit thereof.

Having thus fully described my invention, what I claim as new and useful and desire to procure by Letters Patent is;

1. A locking bar for rail joints comprising a longitudinally extending plate having locking recesses in its upper edge adapted to receive the nuts, end flanges and a central flange extending outwardly from the lower edge of the plate to provide means for securing the said plate to the ties and a centrally located member projecting upwardly from the upper edge of the plate to engage the rail flange and said plate also having strengthening ribs extending longitudinally of the plate and in line with the locking recesses substantially as described.

2. A locking bar for rail joints comprising a longitudinally extending plate having locking recesses in its upper edge adapted to receive the nuts, end flanges and a central flange extending outwardly from the lower edge of the plate to provide means for securing the said plate to the ties and a centrally located member projecting upwardly from the upper edge of the plate to engage the rail flange and said plate also having strengthening ribs extending longitudinally of the plate and in line with the locking recesses, a plate having a projecting rib extending upwardly on one of the sides of the plate providing means for holding the locking bar secure in position substantially as described.

HENRY N. NORTHOFF.
